(57) **CLAIM**

The ornamental design for a container with lid, as shown and described.

DESCRIPTION

FIG. 1 is a front perspective view of the new design for a container with lid;

FIG. 2 is a front elevational view thereof;

FIG. 3 is a rear elevational view thereof;

FIG. 4 is a right side elevational view thereof, with the left side being a mirror image;

FIG. 5 is a top plan view thereof;

FIG. 6 is a front perspective view of an embodiment at a certain length thereof;

FIG. 7 is a front elevational view thereof;

FIG. 8 is a rear elevational view thereof;

FIG. 9 is a right side elevational view thereof, with the left side being a mirror image;

FIG. 10 is a top plan view thereof;

FIG. 11 is a front perspective view of another embodiment at a certain length of the new design for a container with lid;

FIG. 12 is a front elevational view thereof;

FIG. 13 is a rear elevational view thereof;

FIG. 14 is a right side elevational view thereof, with the left side being a mirror image;

FIG. 15 is a top plan view thereof;

FIG. 16 is a front perspective view of another embodiment at a certain length of the new design for a container with lid;

FIG. 17 is a front elevational view thereof;

FIG. 18 is a rear elevational view thereof;

FIG. 19 is a right side elevational view thereof, with the left side being a mirror image; and,

FIG. 20 is a top plan view thereof.

The separation and bracket in FIGS. 1-7 indicates that the particular length of the container is not claimed.
